UNITED STATES PATENT OFFICE.

ROBERT L. YOUSE, OF PHILADELPHIA, PENNSYLVANIA, ASSIGNOR OF ONE-HALF TO
AARON HENDRICK, OF PHILADELPHIA, PENNSYLVANIA.

TRAIN CONTROL.

1,386,482.

Specification of Letters Patent.

Patented Aug. 2, 1921.

Application filed August 28, 1918. Serial No. 251,770.

To all whom it may concern:

Be it known that I, ROBERT L. YOUSE, a citizen of the United States, residing at 2906 N. Leithgow St., Philadelphia, in the county 5 of Philadelphia and State of Pennsylvania, have invented new and useful Improvements in Train Controls, of which the following is a specification.

This invention relates to train-controlling devices, and has more particular reference to what are usually termed automatic signaling and braking devices.

The main object of my invention is to provide a train control which is positive in operation, efficient in action, and one that automatically retards and stops the locomotive or train, should the said locomotive be driven beyond the signal or into a danger zone.

A further object of my invention is to provide a train control which is automatically operated by a tripping device carried on the locomotive, and which co-operates with the engine throttle for cutting off the steam supply, and at the same time automatically applying the brake, should the engineer or trainman pass a danger signal.

With these and other objects in view, as will hereinafter be more apparent, the invention comprehends the provision of an electric switch operating in conjunction with the semaphore, said switch being in circuit with a tripping device at the side of the track, and said tripping device being adapted to automatically close the throttle and shut off the steam, while at the same time means are brought into operation for applying the braking mechanism.

In the further disclosure of the invention, reference is to be had to the accompanying drawings, constituting a part of this specification, in which similar characters of reference denote corresponding parts in all the views, and in which—

Figure 1 is a fragmentary end elevation of a portion of a railroad track and signaling device, including my improvements.

Fig. 2 is a similar fragmentary end elevation, but showing the controlling device in the danger position.

Fig. 3 is a detail sectional elevation of the tripping device which shuts off the throttle.

Fig. 4 is a fragmentary sectional elevation of that part of the mechanism which automatically closes the throttle and applies the

brake, should the locomotive enter a danger zone.

Fig. 5 is an enlarged sectional elevation on the line 5—5 in Fig. 4.

Fig. 6 is a detail sectional elevation of the switch operating in conjunction with the semaphore.

Fig. 7 is an end view of the same.

Fig. 8 is an enlarged detail plan of the means for holding or retaining the automatic controlling device in the open or operative position, and

Fig. 9 is a sectional elevation of the same.

Fig. 10 is a diagrammatic sketch showing the wiring circuits from the battery to the solenoid and switch.

In the accompanying drawings which illustrate a preferred embodiment of the invention, the numeral 10 indicates a rail and adjacent which is provided a signal post 11, on which are mounted the customary home and distance semaphores or signal arms 12 and 13 respectively, said arms being operated in any of the well-known ways. To one side of the rail 10 at either or both sides of the track, I fit or otherwise suitably attach a box-like casing 14 in which is transversely mounted a shaft 15, under the action of a recoil spring 16, said shaft having attached at its inner end—that is to say, on the inner side of the rail—an arm 17 which normally occupies a horizontal position, as indicated by the dotted lines in Fig. 3. At the other or outer end of the shaft 15 is keyed or otherwise secured, a toothed pinion 18 in gear with a rack 19 which is formed integral with a solenoid plunger or piston 20, which is adapted when the solenoid 21 is energized, to be retracted and thereby impart to the shaft 15 a quarter turn, which will swing the arm 17 from a horizontal to a vertical position, as indicated by the dot-and-dash line 17^a in Fig. 3, or the full-line position as shown in Fig. 2. Leads 22 connect the solenoid 21 with a storage battery (not shown) and which may be located at a distance from the track, or placed in any appropriate damp-proof chamber adjacent said track.

Referring more particularly to Figs. 1 and 2, a wheel or bogie 23 is shown, and the numeral 24 designates part of the bed or under-frame of a locomotive, beneath which is suitably secured a storage cylinder or reservoir 25 containing compressed air. From

this cylinder or reservoir 25 a pipe 26, which serves as a conduit, is led to a cylinder 27 (Figs. 4 and 5) and it is to be particularly noted that the conducting pipe 26 is so arranged that there is a downward inclination toward the reservoir 25. At any suitable and appropriate position on the conducting pipe I fit a valve 28, the stem 29 whereof is downwardly extended and passes through a supporting bracket 30 appropriately secured to the under-frame 31 of the locomotive. The stem 29 as will be more clearly seen in Fig. 4, is fitted at its extreme lower end with a laterally extending arm 32, and it is under the action of a recoil spring 33, which normally tends to keep the arm 32 turned into a position at right-angles to the road-bed or track 10. In other words, this arm 32 is retained in the position stated, that is to say, with the valve 28 closed to shut off the compressed air. Or, in other words, the arm 32 is normally retained in a position whereby when the aforesaid arm 17 is swung into a vertical position, they will engage with one another, and the arm 32 will be swung in a horizontal plane through an angle of approximately 90 degrees, which will open the valve 28 and permit of a flow of compressed air to the cylinder 27, which will move the piston 34 in opposition to a strong compression spring 35. This piston 34 is provided with a piston rod 36 which extends beyond the end of the cylinder 27, through an appropriate gland or housing 37, and engages in a second piston 38 having a series of fine holes 38^a therethrough and adapted for movement in a secondary cylinder 39. A rod or piston 40 is connected to the piston 38 and extending through the end of the cylinder 39, and a bearing 41 thereon is provided with an enlarged head 47 which abuts a strong compression spring 42. Mounted at any desired position on the rod 40 there may be provided a depending arm 43 adapted for sliding longitudinally with a second rod 44, which rod 44, as will hereinafter be better understood, may appropriately be parallel with the throttle-controlling rod 45. Obviously the fine holes 38^a must be provided in the pistons 38, to permit the air compressed when said piston 38 is moved forward to pass to the rear side thereof.

In the drawings and on reference more particularly to Figs. 4 and 5, it will be seen that the rod 40 is connected by a spring influenced pin and slot connection 48 in the enlarged head 47 with an extension 46^a on a blade or bar 46, said bar 46 in turn being attached at its other end by a headed part 45^a to the throttle rod 45. Formed integral with or attached to the aforesaid enlarged head 47 is a blade 49, the opposite end whereof is notched out, as shown at 50, and passes through a slotted casing 51, said cas-

ing in turn housing a latch 52, under the action of a spring 53, said latch being fitted with a roller 54 which rides over the notched-out part 50 of the blade 49. This latch 52 serves to lock the throttle lever 55 in engagement with the blade or bar 46 above referred to, so that the throttle may be actuated thereby under normal conditions. On the other hand, when the locomotive passes beyond a danger signal or enters a danger zone, it automatically brings the controlling mechanism into operation, and the piston 34 is brought under the action of the compressed air, whereupon the piston rod 36 moves the headed part 45^a and blade 49 in opposition to the spring 42 until the pin in the slotted connection 48 has traversed the length of the slot. This movement of the blade 49 due to the pin and slot connection 48 causes the roller 54 to ride up over the notched-out part 50, which raises the latch 52 and disengages the throttle lever 55 from connection with the throttle rod 45. This instantaneous disconnection of the throttle lever 55, in the event of imminent danger, automatically prevents the throttle lever 55 from being thrown forwardly and striking the driver, a feature which I have found is common to many of the throttle-controlling mechanisms heretofore constructed. Obviously the return of the throttle lever 55 to operative connection with the blade or bar 46 to re-apply steam will be manually effected by moving the said lever over to the left hand in Fig. 4 which will bring the latch 52 again into latched connection therewith.

In order to provide means for locking the aforesaid valve 28 in the open position, and releasing the same from the open, I secure to the aforesaid stem 29 appropriately on the upper part of the bracket 30, a toothed cam 57 with which engages a spring-influenced dog 58, as will be clearly seen on reference to Figs. 8 and 9. Vertically movable in the bracket 30, I arrange a rod 59, formed with a tit or projection 60, which is normally held down in said bracket 30, by a compression spring 61, located about the lower end of the rod 59. In order to release the dog 58 from engagement with the toothed cam 57, the rod 59 is upwardly moved through any appropriate connection such as a chain 62, a pin 59^a limiting said movement so that the tit 60 can only contact with the heel 58^a of the dog 58.

From the foregoing it will be readily seen that when a pull is exerted on the chain 62 by the engineer the tit 60 will cause dog 58 to swing on its pivot and thus free the cam 58 whereby stem 29 will be turned by the recoil of the spring 33 to close the valve 28 and the springs 42 and 56 will turn the parts 46, 38 and 34 to their normal positions. If necessary an escape valve, not 130

shown, may be placed in the cylinder 27 to permit the escape of compressed air therefrom.

Referring to Figs. 6 and 7 which illustrate a preferred form of switch, the numeral 63 indicates a cylindrical casing in which is mounted a slideable plunger 64, having operative connection by a rod 65^a with the semaphore arm 13, and said plunger 64 is formed with a circumferential groove 65, with which is adapted to engage a pin 66. This pin 66 is housed in a bearing 67 and it passes through a fiber or insulating plate 68, on which is mounted the switch element 69, which is hingedly mounted to a bracket 70 and provided at its end with a contact 71. A wire 72 extends from the bracket 70 to battery 72^b and this battery is connected by wire 73 with the solenoid 21, the solenoid 20 being connected by a wire 73^b with contact 74 with which the contact 71 of the switch will engage when the member 64 has been moved into the position shown in Fig. 6 by the raising of the semaphore arm. In this 25 position of the parts the circuit is closed to solenoid 21 so that the arm 17 will be moved to a position to engage the valve operating means on the locomotive.

In order to provide a means for associating my train control with the ordinary air-braking mechanism, I provide the cylinder 36 with a branch connection 75 which communicates by a pipe 76 with a valve 77, which is made adjustable so that the amount of air 30 to apply the brakes may be regulated and controlled. The valve 77 is fitted with a sealing cover 78 so that said valve is completely inclosed or housed and cannot be tampered with after it is once set and regulated. This valve 77 connects with a brake cylinder 79 in which is located a spring-influenced piston 80, the piston rod 81 whereof extends outwardly and is fitted with a collar 82 to which is fitted a link 83 40 having pivotal connection with a controlling lever 84, said lever being provided with a projection adapted for engagement with a toothed sector 85, and said controlling lever 84 operating to control the ordinary engineer's brake control valve. It will be readily seen that with this automatic and 45 adjustably controlled mechanism, that the degree of braking pressure can be accurately regulated.

From the foregoing description it will be readily seen that by my improvements there is provided an extremely effective train control, and one in which the valve-throwing lever is instantaneously disconnected from 50 connection with the throttle, should danger be imminent. Furthermore, the braking of the train is automatically effected, while the

closing of the throttle valve to cut off the supply of steam to the cylinders is also automatically effected, so that if the signal 65 is set at danger, the engineer cannot pass said signal by inadvertence, accident or mistake.

Obviously a duplication of the automatic control will be found particularly advantageous when it is requisite that trains run in either direction, or where a great range of signaling is possible. In other words, one apparatus or control may be employed when the train is traveling in one direction, 75 and the other control when the train is traveling in the opposite direction.

While I have briefly described one practical embodiment of my invention, I wish it to be understood that I do not limit myself in any way to the precise details, as various changes and other combinations of the several parts may be effected without in any way departing from the spirit or scope of my said invention, such changes or other 85 combinations being only limited by the scope of the appended claims.

I claim:

1. In a train control apparatus, a compressed air tank on the locomotive, a cylinder also on the locomotive, a pipe connecting the tank with the cylinder, a valve in said pipe, a stem connected with the valve, an arm on the valve adapted to engage an obstruction along the track to cause the valve to open, a spring for normally holding the valve in closed position, ratchet mechanism for holding the valve in open position against the action of the spring, manually operated means for releasing the 100 ratchet mechanism to permit the spring to close the valve, a piston in the cylinder and means connected therewith for closing the throttle and applying the brakes.

2. In a train control apparatus, a compressed air tank on the locomotive, a cylinder on the locomotive, a pipe connecting the tank and cylinder together, a valve in said pipe, means for opening the valve by an obstruction along the track, a piston in said 110 cylinder, a second cylinder, a piston therein, a rod connecting the two pistons together, means for connecting the second piston with the throttle controlling mechanism, latching means for detachably connecting the 115 throttle lever with the throttle rod and means, including a blade, associated with the means for connecting the second piston with the throttle mechanism for causing the latching means to release the lever upon the 120 initial movement of the piston.

In testimony whereof I affix my signature.

ROBERT L. YOUSE.
